Des. 671

Charles Chinnock, of New York, N.Y.
Letters Patent No. 671, Dated Oct. 17, 1854.

The Schedule referred to in these Letters Patent and making part of the same
To all whom it may concern.

Be it known that I, Charles Chinnock, of the City, County, and
State of New York, have invented or produced a new ornamental design for the front of a
clock case which I term the "Harlem Gothic," and I do hereby declare that the following
is a full, clear and exact description of the same, reference being had to the accompanying
drawing forming part of this specification, in which,

Fig. 1. is a front elevation of a clock case front of my design.

Fig. 2. is a vertical section of the same through the center.

Fig. 3. is a horizontal section of the same in the line p. y. of Fig. 1.

Similar letters of reference indicate corresponding parts in the several Figs.

The character of this design as its name implies, is Gothic. It consists
of an arched frame A. A. containing a flat panel B. Flanked on its sides by pillars C. C. and
butresses D. D. the whole being supported by a base E. The base has panels a. a; the butresses
have panels b. b; and the pillars have panels c. c., and bases d. d. and are surmounted
by pinnacles F. F. which are ornamented with crockets e. e. and finials f. f. The arch is
ornamented with crockets g. g. and a finial h; and the butresses are also surmounted
by crockets i. i. The panel is ornamented between the arch, and the opening b. which
receives the clock face, with tracery j. j. and at the lower corners with tracery k. k. repre-
senting spandrels.

This design is more particularly intended for casting in iron or other
metal, and in that case will consist of a plate, every part of which is as light as con-
sistent with strength.

2

Des. 671

What I claim as my invention or/production and desire to secure by
Letters Patent is:-

The design and configuration of the clock case front herein described and repre-
sented in the accompanying drawings, and termed the "Harlem Gothic" pattern.
